HOOD CATCH

Filed April 16, 1931

INVENTOR.
RAYMOND G. MOORE
BY
S. M. Mather,
ATTORNEY

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

HOOD CATCH

Application filed April 16, 1931. Serial No. 530,519.

The present invention relates to improvements in hood catches, particularly for automobiles, and has for an object to provide a catch disposed at the inside of the hood and having an operating handle at the outside, which will effectually hold the hood downwardly and inwardly, and may be operated to engaged or disengaged relation with a minimum of effort. It has been found that, because of variations in the mounting of the keeper bar on the automobile frame, and the mounting of the catch device on the hood, the engaging angle varied between them, and it is proposed in the present invention to provide a catch device in which an inclined keeper engaging means is provided which will remain at the same angle in any position of relative movement of the device, so that its operative and functional relation with respect to the keeper bar remains constant, despite variations in the mounting.

With the above and other objects in view, an embodiment of the invention is shown in the accompanying drawing and this embodiment will be hereinafter more fully described with reference thereto, and the invention will be finally pointed out in the claims.

In the drawing:

Fig. 1 is a side elevation of a hood catch, according to the exemplary embodiment of the invention disclosed herein, the hood to which it is attached being shown in vertical section.

Fig. 2 is a rear elevation of the same.

Fig. 3 is a side elevation showing the catch engaged with the keeper bar, the hood being shown in vertical section.

Fig. 4 is a plan view of the catch in operative relation with the keeper bar, the hood being shown in horizontal section.

Similar reference characters indicate corresponding parts throughout the several figures of the drawing.

Referring to the drawing, the hood catch, comprises a sheet metal bracket plate 10 having a slot 11 adapted to register with a slot 12 in the hood 13, and adapted to be secured to the inner side of the hood, as by rivets 14.

Parallel side plates or ears 15—15 are bent

inwardly at right angles from the vertical edges of the plate 10.

A lever member comprising a handle portion 16, disposed exteriorly of the hood, a box portion 17 and an arm portion 18, disposed interiorly of the hood, is pivotally mounted within the bracket upon a transverse pin 19 engaged through the box portion 18. The lever, as shown, is formed of sheet metal, the handle portion 16 being bent into tubular form while the box and arm portions are of inverted U-shape in cross-section.

The sides of the lever member are inwardly spaced from the side plates 15, and in straddling relation to the arm portion 18 there is provided a keeper engaging member 20 of inverted U-shape in cross-section pivotally mounted upon a cross pin 21 extending through said arm portions and provided at the lower ends of its side portions, which project below said arm portion, with a cross-pin 22 having its ends slidably engaged in arcuate slots 23 provided in the side plates 15.

Within the box portion 17 a coil spring 24 is disposed about the cross-pin 19 and has its end extended into the arm 18 beneath the pin 21 to constantly urge the lever and the keeper engaging member upwardly, the upward movement being limited by abutment of the pin 22 in the upper ends of the slots 23. For the purpose of convenient assembly the pin 19 has a slot 25 extending from one end and in which the inner end of the spring is engaged and anchored, the split end of the pin being engaged in substantially semi-circular openings 26—26 divided by a bar portion 27, disposed in the slot 25 and adapted to prevent turning of the pin. The other end of the pin is provided with a head 28, and a cotter pin 29 is inserted through the split end to prevent withdrawal.

The upper surface 30 of the keeper engaging member 20 is inclined downwardly toward the inner side of the hood and upon engagement with the keeper bar 31, suitably supported on the automobile structure, exerts a downward and inward pull on the hood under pressure of the spring 24.

The catch is engaged with the keeper bar by depressing the lever and keeper engaging

member to a point where the latter will swing beneath the keeper bar and thereupon releasing it so that it rises into engagement with the keeper bar. The arrangement of the pivot pin 21, with respect to the axis of the pin 19 and the arc of the slot 23, is such that in any position of rotation of the lever the angle of the surface 30 remains the same, so that irrespective of variations in the mounting 10 its relation to the keeper bar and its consequent functioning are constant.

I have illustrated and described a preferred and satisfactory embodiment of the invention, but it will be obvious that changes may 15 be made therein, within the spirit and scope thereof, as defined in the appended claims.

Having thus described my invention what I claim and desire to secure by Letters Patent is:—

- 20 1. In a hood catch, a catch element and a keeper element, one of said elements having an engaging surface adapted to move in a direction non-parallel to a given line to engage the other element to hold the hood closed, actuating means for moving said last mentioned element into and out of engagement with the other element, and means adapted to maintain a constant angle of said engaging surface with respect to said given line in any position of said actuating means.
- 25 2. In a hood catch, a catch element and a keeper element, one of said elements having an engaging surface adapted to move in a direction non-parallel to a given line to engage the other element to draw the hood downwardly, pivoted means for moving said last mentioned element into and out of engagement with the other element, and means adapted to maintain a constant angle of said 30 engaging surface with respect to said given line in any position of said pivoted means.
- 35 3. In a hood catch, a catch element and a keeper element, one of said elements having an inclined engaging surface adapted to move in a direction non-parallel to a given line to engage the other element to draw the hood downwardly, actuating means for moving said last mentioned element into and out of engagement with the other element, and means adapted to maintain a constant angle of said 40 inclined engaging surface with respect to said given line in any position of said actuating means.
- 45 4. In a hood catch, a catch element and a keeper element, said catch element comprising a support, an operating lever pivotally mounted in said support, a keeper engaging member having an engaging surface movable in a direction non-parallel to a given line 50 and adapted to be moved into and out of engagement with said keeper through operation of said lever, and means adapted to maintain a constant angle of said engaging surface with respect to said given line in any 55 position of said lever.

5. In a hood catch, a catch element and a keeper element, said catch element comprising a support, an operating lever pivotally mounted in said support, a keeper engaging member pivotally mounted on said lever and having an engaging surface movable in a direction non-parallel to a given line and adapted to be moved into and out of engagement with said keeper through operation of said lever, and means adapted to maintain a constant angle of said engaging surface with respect to said given line in any position of said lever.

Signed at Bridgeport, county of Fairfield and State of Connecticut, this 27th day of March, 1931.

RAYMOND G. MOORE.
